DRAWER PULL

Dudley B. Pope, Bridgeport, Conn., assignor to
 The Bassick Company, Bridgeport, Conn., a
 corporation of Connecticut

Application March 22, 1937, Serial No. 132,441

2 Claims. (Cl. 41—34)

The present invention relates to drawer pulls, particularly for furniture drawers, and has for an object to provide a pull of simple and inexpensive construction which may be easily attached to the furniture, and which lends itself to the carrying out of various designs of a modernistic character. In designs of this type the drawer pull is very often constructed of the same material as the drawer, that is, of wood and appears to be an integral part of the drawer, rather than an attachment as is the case of ordinary drawer pulls. It is proposed to provide a pull construction which will enable this effect to be carried out, and at the same time will permit of the ready attachment or detachment of the pull. In this connection it is proposed to provide metal parts constituting a part of the structure and securing the pull in place, and which also combine with the wood or other material forming the body of the pull to produce an ornamental design. It is further proposed to make the metal parts and the body easily detachable with respect to the furniture and to each other so that they may be cleaned, without danger of soiling the furniture, this being of particular importance in the case of metal parts that may become tarnished, especially where such metal parts are used upon light colored wood furniture.

A further object is to provide the metal parts, so that they will interlock with the pull body, and with each other, and will be rigidly secured in assembled relation simply by tightening of the attachment screw, which also secures the pull assembly to the drawer.

With the above and other objects in view, an embodiment of the invention is shown in the accompanying drawing, and this embodiment will be hereinafter more fully described with reference thereto, and the invention will be finally pointed out in the claims.

In the drawing:

Fig. 1 is a front elevation of the drawer pull, according to the exemplary illustrated embodiment of the invention.

Fig. 2 is a plan view of one end of the drawer pull showing the same attached to a drawer, it being understood that the other end is identical, but reversed.

Fig. 3 is an end view showing the pull attached to the drawer.

Fig. 4 is a horizontal sectional view, taken along the line 4—4 of Fig. 3.

Fig. 5 is a vertical sectional view, taken along the line 5—5 of Fig. 2.

Fig. 6 is a perspective view showing one end of the body part of the drawer pull and the metal parts in separated relation with respect thereto.

Similar reference characters indicate corresponding parts throughout the several figures of the drawing.

Referring to the drawing, the drawer pull body 10 is in the form of an elongated strip of suitable material, as wood, bakelite, or the like, and is of any suitable cross-section depending upon the particular design. At each end it is recessed at its front face, as at 11, the recess terminating at its inner end in a shoulder 12 which forms one extremity of the central panel 15 portion of the pull, the other end of the recessed portion being rounded to the rear surface, as at 13, or otherwise suitably formed, depending upon the design. An aperture 14 extends through the end of the body portion in outwardly spaced relation to the shoulder 12 and is adapted to be aligned with the screw receiving hole 15 provided in the drawer 16.

Upon the surface of the recessed portion 11 and its rounded end 13 there is engaged a metal plate 17 shaped to conform to the surface thereof, the inner end of this plate abutting the shoulder 12 and the upper and lower edges being flush with the upper and lower surfaces of the body portion 10. An aperture 18 is provided in the plate 17 in alignment with the aperture 14 of the body portion. The plate as shown is provided with a cutout along its end portion 19 for decorative purposes.

A U-shape clip member 20 is engaged over the plate 17 and over the upper and lower surfaces of the body portion 10 to thus secure both itself and the plate 17 against movement relatively to the body portion. The vertical portion of this clip member is provided at its inner side with an interiorly threaded tube 21, which is welded, brazed, soldered or otherwise suitably secured thereto, and which is adapted to engage through the aperture 18 of the plate 17 and in the aperture 14 of the body portion, where it is engaged by the threaded end of the attaching screw 22, which upon being tightened secures the plate 17 and clip 20 in place upon the body portion and secures the entire assembly to the drawer 16. It will be understood that the body portion 10, as well as the plate 17 and clip member 20, may be varied in shape and have suitable surface ornamentation provided thereon.

I have illustrated and described a preferred and satisfactory embodiment of the invention,

but it will be obvious that changes may be made therein, within the spirit and scope thereof as defined in the appended claims.

Having thus described my invention, what I claim and desire to secure by Letters Patent is:—

- 5 1. A drawer pull structure comprising a body member having an aperture, a clip member adapted to be engaged over said aperture to enclose it and adapted to engage the upper and lower surfaces of said body portion, threaded means on said clip member engaging said aperture, a plate member having a portion disposed between said clip member and said body member and having an aperture engaged by said 10 threaded means, and a screw adapted to extend through said body member aperture from the rear to secure said clip member in place.
- 15

2. A drawer pull structure comprising a body member having an aperture and a shoulder inwardly spaced from said aperture, a clip member adapted to be engaged over said aperture to enclose it and adapted to engage the upper and lower surfaces of said body portion, threaded means on said clip member engaging said aperture, a plate member having a portion disposed between said clip member and said body member and having an aperture engaged by said 10 threaded means, the inner end of said plate member abutting said shoulder, and a screw adapted to extend through said body member aperture from the rear to secure said clip member in place.
